[57] CLAIM

The ornamental design for a vented dock float case, as shown and described.

DESCRIPTION

FIG. 1 is a top perspective view of a vented dock float case

1 Claim, 6 Drawing Sheets

showing my new design, the broken lines are for illustrative purposes only and form no part of the claimed design;

FIG. 2 is an end elevational view thereof, the opposite end view being a mirror image of that shown;

FIG. 3 is a side elevational view thereof, the opposite side view being a mirror image of that shown;

FIG. 4 is a bottom plan view thereof;

FIG. 5 is an enlarged cross sectional view taken along line 5—5 of FIG. 7;

FIG. 6 is an enlarged cross sectional view taken along line 6—6 of FIG. 10;

FIG. 7 is a fragmentary perspective view of FIG. 1, it being cut-away and pulled-away to show the core;

FIG. 8 is an enlarged end cross sectional view taken along line 8—8 of FIG. 7;

FIG. 9 is an enlarged end cross sectional view taken along line 9—9 of FIG. 10;

FIG. 10 is a top and side perspective view of a second embodiment of the vented dock float case, the opposite side and end views being a mirror image of that shown, and the bottom is flat and unornamented; and,

FIG. 11 is an enlarged fragmentary exploded view of the vented dock float case and plug.
